CLAIM

The ornamental design for a clipper organizer, as shown and described.

DESCRIPTION

FIG. 1 is a perspective view of a clipper organizer showing our new design, with hair clippers depicted in dashed lines and being no part of the claimed design;

FIG. 2 is another perspective view of the clipper organizer;

FIG. 3 is a front elevational view of the clipper organizer;

FIG. 4 is a rear elevational view of the clipper organizer;

FIG. 5 is a left side elevational view of the clipper organizer;

FIG. 6 is a right side elevational view of the clipper organizer;

FIG. 7 is a top view of the clipper organizer; and,

FIG. 8 is a bottom view of the clipper organizer.
